PANTY GIRDLE

Herbert Barg, Merion, Pa., assignor to True Form Foundation, Inc., Darby, Pa., a corporation of Pennsylvania

Filed Aug. 25, 1966, Ser. No. 3,592

Term of patent 14 years

(Cl. D2—4)

FIG. 1

FIG. 2

FIG. 3

FIG. 4

FIG. 6

FIG. 7

I claim:

The ornamental design for a pancy girdle, substantially as shown.
